UNITED STATES PATENT OFFICE.

ELMER E. HEATH, OF SMETHPORT, PENNSYLVANIA.

PIN-SETTING APPARATUS FOR BOWLING-ALLEYS.

No. 857,989.

Specification of Letters Patent.

Patented June 25, 1907.

Application filed November 25, 1905. Serial No. 289,106.

To all whom it may concern:

Be it known that I, ELMER E. HEATH, a citizen of the United States, residing at Smethport, in the county of McKean and State of Pennsylvania, have invented certain new and useful Improvements in Pin-Setting Apparatus for Bowling-Alleys, of which the following is a specification, reference being had therein to the accompanying drawing.

10 This invention relates to improvements in bowling pin setters for bowling alleys.

It pertains particularly to a pin carrying and setting frame which is adapted to operate on two or more alleys.

15 Among the objects of the invention is to provide a triangular pin carrying and setting frame which is pivoted to swing from one alley to the other and is adapted to be operated by one man for setting the pins on the alleys.

20 Another object is to provide for the proper placing of the pins upon the pin spots by automatically actuated devices which first permit the pin to drop upon the alley and then 25 act to place it accurately upon the pin spot.

Other objects of the invention will be manifest from the description of the mechanism embodying my improvement, which is herein shown and described for the purposes of 30 illustration.

Figure 1 is a perspective view showing two parallel bowling alleys provided with a pin setter embodying my improvements. Fig. 2 is a bottom plan view of a pin carrying and setting frame embodying my improvements, showing the parts in their normal positions when the frame is elevated above the alley. Fig. 3 is a top plan view of the frame shown in Fig. 2, with the parts in the position which 35 they take when the frame has been lowered 40 to set the pins on one alley and to place them on the desired pin spots. Fig. 4 is a vertical section on the line 4—4 of Fig. 3. Fig. 5 is a vertical section on the line 5—5, Fig. 2. Fig. 45 6 shows in perspective a portion of a co-operating pair of pin setting slats and a portion of a side wall of the frame adjacent to one end of said slats. Fig. 7 is a vertical section on the line 4—4, Fig. 3, showing the position of 50 the parts immediately after the laterally reciprocating slats have snapped back away from the pins which they have just directed on to the pin spots. Figs. 8 and 9 show details.

55 In the drawings 1 indicates as an entirety a bowling alley of any preferred construction

and 2 a similar alley arranged parallel to the first one.

3 indicates a pit at the rear ends of the alleys it being divided into sections by means 60 of a dividing board 3' each section being adapted to receive the pins from one of the alleys.

4—4 indicate the cushions or buffers at the back of the pit, these being of any preferred construction.

5 indicates as an entirety the pin setting apparatus. It comprises primarily a revolute frame or standard 5' supported by a suitable frame work and it in turn supporting the pin carrying and setting frame which is indicated as an entirety by 6. The standard 5' is preferably hollow throughout its length and is fitted over and is revolute about a brace or standard rod 5^b, which is 70 secured at its lower end to the floor of the alley and at its upper end to the ceiling of the room or to some other suitably rigid structure.

5^c is a thrust ball-bearing arranged between the lower end of the hollow support or standard 5' and the floor. The standard 5^b may be longitudinally adjustable to adapt it to rooms of different heights. For the purpose of illustration I have indicated the upper end of the said standard as formed in two parts, one recessed and the other provided with a tongue adapted to engage the walls of said recess and to be held in any position of adjustment therein by means of a 80 set screw 5^d.

7 indicates a bracing frame for the revolute hollow support 5'. This frame 7 preferably comprises vertically arranged rods 7', 7'', arranged at either side of the standard 5' 95 and each connected at its upper end to the ceiling in any preferred manner and each connected to the other at its lower end by a cross member 7^a which carries at its center a collar 7^b loosely fitted to the said revolute standard or support 5'.

8 is a hand wheel secured to the support 5' and adapted to facilitate rotation by hand of the said standard or support. The pin carrying and setting frame 6 may be attached to its revolute carrier or support 5^e in any suitable manner so as to permit the vertical or up and down movement of the said frame relative to the said carrier or support while at the same time being adapted to 105 cause the frame to rotate with the said support or standard.

For the purposes of illustration I have shown a connection between the support and the pin frame comprising a laterally extending plate or arm 9 having one end fitted to the said support or standard and adapted to move up and down relatively thereto and carrying a guide or lug 9' which engages with the walls of a vertical, longitudinal groove 5^c in the said support or standard 5'. At its other end this plate or arm 9 is rigidly secured to and supports the adjacent end of the pin carrying and setting frame 6. By means of this connection between the frame and its supporting standard it will be seen that the frame can be moved up and down relatively to the standard and rotated with it. To facilitate the operation of the mechanism I have found it advisable to have the frame counterbalanced in such manner that it can be raised and lowered with ease. This balancing is accomplished by means of a weight 10 suspended from a pulley 11 carried by an arm 5^e at the upper end of the revoluble support or standard 5'. The weight is preferably suspended at one end by a cord or rope 12, the other end of which is connected to the end or corner of the frame 6 nearest the revoluble support 5'. The weight should be sufficient to counterbalance the weight of the frame 6 when it is loaded with its full complement or set of pins. It will thus be seen that the frame can be raised or lowered with ease, and that after it has deposited the pins on the pin spots, or, in other words, when it is empty of pins, the tendency of the weight 10 will be to elevate the frame above the alley.

9^a is an opening through the arm 9 through which the weight 10 may pass up and down during the relative up and down travel of the weight and arm.

The pin carrying and setting frame 6 is preferably triangular in form and has, as previously described, one of its corners rigidly secured to the standard engaging plate or arm 9. The vertical bounding walls or sides of the frame are indicated by 6', 6^a and 6^b. Near their lower edges the walls 6^a and 6^b are longitudinally grooved substantially parallel with the surface of the alley as indicated at 6^c and adapted to receive the adjacent ends of the co-operating pairs of laterally reciprocating slats which form the perforated bottom of the frame, as well as the means for accurately placing the pins on the pin spots after they have been dropped on to the alley. The pairs of slats are indicated respectively by 13—13'; 14—14'; 15—15'; and 16—16', each slat of each pair extending from the wall 6^b to the wall 6^a. The slats of each pair are normally held apart from each other and this may be accomplished in various ways. For the purpose of illustration I have indicated the slats 65 13—14 connected together by straps or bars

17—17; the slats 13' and 14' connected by a strap or bar 18; the slats 14 and 15 connected together by the straps or bars 19; the slats 14' and 15' connected together by the straps or bars 20—20; the slats or bars 15 and 16 connected together by the straps or bars 21—21 and the slats 15' and 16' connected together by the straps or bars 21—21'.

22 indicates recesses or grooves extending vertically through the slats. There are as many of these grooves or recesses in each slat as the number of pins which the slat is adapted to set up. The grooves or recesses of the slats of each co-operating pair of slats 80 are arranged in alinement with each other or so as to register with each other in order to form openings 22' through which the pins may freely pass when the slats of each pair are separated from each other. When the 85 slats of each pair are closed together these openings 22' are of such diameter as to have their walls engage the walls of the pin extending through them and to insure that the pin will occupy a definite fixed position relative 90 to the others in the frame.

23 indicate spiral springs arranged between the slats of several of the pairs of slats and adapted to normally hold all of the slats apart the spring, force being transmitted 95 through the straps or bars connecting the various slats together to attain this result.

24 indicate rocking or swinging, pin supporting and depositing plates or racks. There are as many of these rocking or swinging plates as there are pairs of co-operating slats at the bottom of the frame 6. These plates are preferably arranged between the walls 6^a and 6^b of the frame and are parallel with the walls 6' thereof. Each of the rocking plates is pivotally mounted at either end near its center to the adjacent wall of the frame as indicated at 24' and is adapted to be rocked about the axis of said pivot. The plates are transversely grooved on their upper surfaces as indicated at 24^a to form what may be considered receiving pockets or grooves in which the pins are to be inserted. Each rocking plate is provided with one or more of these transverse grooves in accordance 110 with its position in the triangular frame and the number of pins which it is to carry and deposit. All of the rocking plates are connected together at their top edges by means of straps or tie rods 25 each extending between the top edges of adjacent plates and hinged at either end to the adjoining edge of the adjacent plate, as indicated at 25'. This construction insures that all of the rocking plates will operate simultaneously at all 115 times.

26 indicate partition or abutment plates arranged in a series and each plate extending between the walls 6^a and 6^b of the frame and being parallel with the wall 6' thereof. 130

These partition or abutment plates preferably extend from a point immediately adjacent the tops of the laterally reciprocating slats at the bottom of the frame to a point 5 slightly above that of the lower end of a pin resting upon one of the rocking plates 24, when the latter is in its initial pin receiving position. The plates 26 are each so arranged within the frame as to co-operate with the 10 rocking plate which has its lower end beneath the top edge of the said partition or abutment plate when the rocking plate is in inclined pin receiving position. Preferably each of these partitions or abutment plates 15 26 is tangent to the curve of the cut-out portion or recess 22' of the laterally reciprocating pin setting slat which is immediately beneath it when the said slat is in its normal position apart from its co-operating slat. 20 The second and fourth rocking plates from the axis of the standard 5' are provided with arms 24^b at either end of the plate which extend at right angles therefrom near the transverse center of the plates. 25 27 are vertical reciprocatable rods or pins extending from points beneath the frame upward through vertically elongated slots 27' in the laterally reciprocating slats immediately beneath the arms 24^b on the said rocking plates. These pins or rods 27 are adapted 30 to engage with the free ends of the said arms 24^b and to rock the arms and the plates 24 about the horizontal axes at 24'. These pins or rods 27 may be normally held in their 35 lowermost position with their lower ends some little distance beneath the frame by means of springs 27^a, each secured at one end to the adjacent bounding wall of the triangular frame and having its other end bearing 40 against a collar 27^b on the said rod or pin. 27^c are guides for the said rods each secured to the adjacent bounding wall of the triangular frame and adapted to guide the rod or pin in its up and down travel and to engage 45 with the collar 27^b when the pin or rod is depressed in order to limit the downward travel of the pin or rod. However, the downward travel of the pins 27 may be actuated by gravity alone instead of by spring pressure 50 when desired.

The lateral movement of the slats of each co-operating pair of pin setting slats, whereby said slats are caused to travel toward each other against the action of the springs 55 23 is effected by means of a mechanism which is indicated as an entirety by 28. Of this mechanism 28' is a transversely arranged shaft mounted at either end in bearings in the adjacent walls 6^a, 6^b, of the triangular frame. Near either end this shaft has secured to it double arm levers 28^a. The free ends of the upper arms of said levers are connected by rods 28^b to the opposite ends of the slat 14 and the lower ends of the under

arms of the levers 28^a are connected by 65 means of rods 28^c to the opposite ends of the slat 14.

28^d is a lever arm rigidly secured to the shaft 28' near its center and arranged at an angle to the arms of the double lever 28^a. 70

29 is a rod or pin for actuating the lever 28^a. This rod or pin extends through a vertical bearing in the plate 13^a arranged in the corner between the walls 6^a and 6^b. Normally this pin 29 extends downward below 75 the bottom of the frame to a distance somewhat less than the normal distance of the bottom of the pins 27 from the bottom of the frame. The rod 29 is preferably formed in two parts hinged together as indicated at 29' 80 in such manner as to have its upper end adapted to swing away from the axis of the shaft 28' under certain conditions.

29^a is a spring secured at one end to the lower part of the rod 29 and having its upper 85 free end bearing against the upper hinged part of the rod 29 and adapted to hold it normally in alinement with the lower part of the rod.

29^b is a collar on the lower part of the rod 90 29 against which the free end of a spring 29^c bears, the other end of this spring being secured to the frame in any suitable manner.

The operation of the mechanism is as follows: Assuming that the pin carrying and 95 setting frame is in elevated position above one of the alleys and that the operator has rocked the series of rocking plates 24 into its inclined pin receiving position, a complement or set of pins, 30, is placed in the frame 100 each pin being dropped into one of the transverse grooves in one of the rocking plates 24 and being held in inclined position on the plate by one of the vertical abutment and guide walls 26. The frame is then lowered to 105 the alley by simply pressing downward upon it, and as soon as the lower edges of the pins 27 engage the floor of the alley, the said pins begin to travel upwardly and to swing the rocking plates 24 about their longitudinal 110 horizontal axes at 24', the walls 26 serving to guide the pins bearing against them downward and at the same time co-operating with the adjacent rocking plates to effect the righting of the pins into vertical position. Shortly 115 after the rods 27 have engaged the floor of the alley and have commenced to rock the plates 24, or as soon as the plates 24 have been rocked so as to be practically parallel with the plates 26 and have dropped the pins 120 through the openings between the slats immediately beneath them, the lower end of the rod 29 engages with the floor of the alley and through the mechanism indicated as an entirety by 28 causes the slats of each co-operating pair of slats to travel laterally toward 125 each other decreasing the area of the openings 22' between the slats and directing the

pins between the slats of each pair of slats onto the precise pin spot desired. As soon as the pins have been properly placed upon their respective spots the upper hinged end of the rod or pin 29 slips from the free end of the arm 28^d and bends back in such manner as to permit the said arm 28^d to rock or swing downward free of the rod 29, this downward swinging of the arm 28 being effected by the springs 23 tending to force the slats of each co-operating pair of slats apart. The frame may then be raised by applying pressure to it upwardly at any point, it being free at all points to rise up and away from the pins without effecting their positions on the spots. As the frame is raised above the alley, the pins or rods 27 drop down to their normal position or are forced down by the springs controlling them as the case may be and the spring 29^e forces the rod 29 down until the upper edge of its upper hinged end, which is cam surfaced as indicated at 29^d, snaps back into proper position under the free end of the arm 28^d. The frame is then swung to the other alley and the rocking plates are swung into pin receiving position and the frame is ready to receive the pins to be set up in this alley.

It will be noted that I have so arranged the frame and the rocking plates relatively to the axis about which the frame is swung, that the pins are properly placed on each alley and that when the frames are above either alley the rocking plates are in the most advantageous position for having the pins placed therein by the operator in the pit.

By arranging the supporting standard between the alleys as shown and connecting the setting frame therewith by one of its corners or apexes it follows that when the frame is swung over one alley one corner is disposed in the central vertical longitudinal plane of the alley; and that when the frame is swung over the other alley, the other free corner of the frame occupies the same relative position to the alley over which the frame rests, that is to say it is in the central vertical longitudinal plane, and pointing to the front, of that alley.

What I claim is:

1. In a pin setting apparatus for bowling alleys, the combination with a pin carrying and depositing frame, of means movable in the frame in planes substantially parallel with the surface of the alley, adapted to engage the pins after they are deposited upon the alley and to arrange them accurately in predetermined relation to each other.

2. In a pin setting apparatus for bowling alleys, the combination of a frame having side walls, for carrying the pins and depositing them in upright position upon the alley, and means carried by the side walls of the frame arranged to slide relatively thereto, for engaging the pins after they are in upright position upon the alley and arranging

them accurately in predetermined relation to each other.

3. In a pin setting apparatus for bowling alleys, the combination of a frame for receiving, carrying and depositing the pins upon the alley, having the side walls and a perforated bottom through which the pins are arranged to pass, the said bottom being formed of separate parts movable relative to each other and arranged to engage with the pins when the frame is set upon the alley and accurately arrange the pins, substantially as set forth.

4. In a pin setting apparatus for bowling alleys, the combination of a frame adapted to receive the pins in inclined position having a perforated bottom through which the pins are adapted to pass formed of separate parts movable relative to each other, means for delivering the pins from the frame and depositing them upon the alley in upright position, and means for operating the movable parts of the bottom of the frame to cause them to engage with the pins after they are deposited upon the alley and to place them accurately in predetermined relation to each other.

5. In a pin setter for bowling alleys, the combination of a frame, a series of rocking pin receiving and depositing slats arranged within the said frame, means for rocking the said slats when the frame approaches the alley in order to deposit the pins on the alley in upright position, and means movable in the frame in planes substantially parallel with the surface of the alley for engaging the pins after they are deposited upon the alley and placing them accurately in predetermined relation to each other.

6. In a pin setting apparatus for bowling alleys, the combination of a frame having a perforated bottom through which the pins are adapted to pass formed of separate parts movable relative to each other, a series of rocking pin receiving and depositing plates arranged within said frame, a series of guiding plates arranged within said frame and adapted to co-operate with said rocking plates to deposit the pins in upright position upon the alley, means for actuating said rocking plates, and means for operating the movable parts of the bottom of the frame to cause them to engage with the pins after they have been deposited upon the alley to place them accurately in predetermined relation to each other.

7. In a pin setting apparatus for bowling alleys, the combination with a frame adapted to receive the pins having a perforated bottom through which the pins pass when being set and means carried by the frame adapted to deposit the pins upon an alley, of means carried by the frame and arranged in the plane of the bottom thereof, adapted to engage with the pins after they have been de-

posed upon the alley and to arrange them accurately in predetermined fixed relation to each other.

8. In a pin setting apparatus for bowling alleys, the combination with a triangular frame adapted to receive the pins having a bottom formed of pairs of slats movable relative to each other and between which the pins pass in being set and means carried by the frame adapted to deposit the pins upon an alley, of means carried by the frame adapted to operate the movable elements of the bottom of the frame to cause them to engage with the pins after they have been deposited upon the alley and to arrange them accurately in predetermined fixed relation to each other, and then to disengage the pins to permit the removal of the frame without disturbing the positions of the pins.

20 9. In a pin setting apparatus for bowling alleys, the combination of a frame, rocking plates arranged within said frame, adapted to receive the pins and to deposit them upon the alley, a series of pairs of co-operating slats 25 having pin apertures therethrough through which the said pins are directed by the said rocking plates, means tending to normally hold the said slats of each co-operating pair of slats apart, and means tending to force 30 the slats of each co-operating pair toward each other after the pins have been deposited upon an alley, whereby the walls of the pin openings between the slats engage the pins therein and arrange them accurately in pre- 35 determined relation to each other.

10. In a pin setter for bowling alleys, the combination with a pair of alleys of a pin carrying and depositing frame for the said alleys, and means for swinging said pin carrying and depositing frame from working position in one alley to working position in the other.

11. In a pin setting apparatus for bowling alleys, the combination of two alleys, a pin setting frame constructed and arranged to be elevated above the alleys to receive the pins and to be lowered to the alleys to deposit the pins thereon, and means for swinging the said frame from working position in 50 one alley to working position in the other.

12. In a pin setting apparatus for bowling alleys, the combination of two alleys, a pin setting frame constructed and arranged to be elevated above the alleys to receive the pins and to be lowered to the alleys to deposit the pins thereon, and means for swinging said frame from one alley to the other and adapted to permit the vertical adjustment of the frame relative to either of said alleys.

13. In a pin setting apparatus for bowling alleys, the combination of a bowling alley and a pit at the pin end thereof, a vertically adjustable pin receiving and depositing frame 65 and a series of rocking plates in said frame

adapted to be inclined to receive the pins and arranged in planes at an angle to the plane of said pit.

14. In a pin setting apparatus for bowling alleys, the combination of a triangular frame 70 adjustable vertically relatively to the alley, and arranged to have one of its inclosing walls transverse to the longitudinal axis of the alley when it is in pin receiving and depositing position, and a series of rocking 75 plates arranged parallel to the said inclosing wall of the frame, each plate of said series being adapted to be inclined to receive a pin or pins and to be rocked into vertical position to deposit the pins in upright position 80 upon the alley.

15. In a pin setting apparatus for bowling alleys, the combination with two bowling alleys, of a rotatable standard arranged near the alleys, and a triangular pin receiving 85 and depositing frame having one corner connected to said revoluble standard and adapted to be revolved with said standard from pin receiving position above the alley to pin receiving position above the other alley. 90

16. In a pin setting apparatus for bowling alleys, the combination with two alleys, of a pivotally supported triangular pin receiving and depositing frame arranged to be swung from one alley to the other, and carrying a 95 series of rocking pin receiving and depositing plates arranged parallel to the base of said triangular frame whose apex is adjacent to the axis about which the frame swings.

17. In a pin setting apparatus for bowling 100 alleys, the combination with a pin receiving and depositing frame, of a series of pairs of co-operating slats carried by said frame, the slats of each pair being normally held yieldingly apart and being provided with mutually co-operating pin recesses or grooves, and means for forcing the slats of each co-operating pair toward each other after the pins are deposited upon an alley, to set them accurately in predetermined relation to each 110 other, and then releasing the slats of each pair and allowing them to spring back into normal separated relation to each other.

18. In a pin setting apparatus for bowling alleys, the combination with two alleys, of a 115 triangular pin-receiving and depositing frame, a pivotal support for the frame arranged between the two alleys and a support or connection between the said frame and pivotal support connected with the former at one of its corners whereby when the frame is in working position over one of the alleys one of its free corners is in the central vertical longitudinal plane of that alley and pointing to the front, and when the frame is swung 120 over the other alley the other free corner of the frame is in the central longitudinal plane of the last said alley and pointing to the front thereof, substantially as set forth. 125

19. In a pin setting apparatus for bowling 130

- alleys, the combination of a vertical standard or support, a pin setting frame supported by the said standard and adjustable vertically thereupon and also free to turn about the 5 vertical axis of the standard, and means for counterbalancing the frame, these means being also free to turn with the frame about the said vertical axis, substantially as set forth.
- 10 20. In a pin setting apparatus for bowling alleys, the combination of a vertical support or standard, a pin setting frame, a supporting arm for the frame mounted upon the support and vertically adjustable relatively

thereto and free to swing about the vertical 15 axis thereof, another arm extending out from the standard above the frame-carrying arm and free to turn therewith about the vertical axis of the standard, and counterbalancing mechanism for the frame supported by last said arm, substantially as set forth.

In testimony whereof I affix my signature in presence of two witnesses.

ELMER E. HEATH.
